UNITED STATES PATENT OFFICE

107,816

DESIGN FOR A BOX OR SIMILAR COSMETIC CONTAINER

Adam Baker Barnhart, New York, N. Y., assignor to Jacqueline Cochran, doing business as J. C. Laboratories, Roselle, N. J.

Application August 9, 1937, Serial No. 70,951

Term of patent 14 years

To all whom it may concern:

Be it known that I, Adam Baker Barnhart, a citizen of the United States, residing at New York, in the county of New York and State of New York, have invented a new, original, and ornamental Design for a Box or Similar Cosmetic Container, of which the following is a specification, reference being had to the accompanying drawing, forming part thereof.

In the drawing which shows my design for a box or similar cosmetic container, Figure 1 is a perspective view thereof; Figure 2 is a side elevation thereof, and Figure 3 is a bottom plan view thereof.

I claim:

The ornamental design for a box or similar cosmetic container as shown.

ADAM BAKER BARNHART.
